UNITED STATES PATENT OFFICE

108,419

DESIGN FOR A FACEPLATE FOR A SEE-GAUGE FOR LIQUID DISPENSING APPARATUS

Eric H. Bradley, Spring Lake, Mich., assignor to John Wood Manufacturing Company, Inc., Conshohocken, Pa., a corporation of Delaware

Application December 4, 1937, Serial No. 73,376

Term of patent 14 years

To all whom it may concern:

Be it known that I, Eric H. Bradley, a citizen of the United States, residing at Spring Lake, in the county of Ottawa and State of Michigan, have invented a new, original, and ornamental Design for a Faceplate for a See-Gauge for Liquid Dispensing Apparatus, of which the following is a specification, reference being had to the accompanying drawing, forming part thereof.

The figure is a front elevational view of a faceplate for a see-gauge for liquid dispensing apparatus. Said plate is but one-fiftieth of an inch thick.

I claim:

The ornamental design for a faceplate for a see-gauge for liquid dispensing apparatus, as shown and described.

ERIC H. BRADLEY.
